AUTOMATIC INTERRUPTER FOR
BROADCAST RECEIVERS

Ralph D. Wichman, Jr., and Robert T. McClellan, Sacramento, Calif., assignors, by direct and mesne assignments, of one-fourth to Emmett J. Peterson, Sacramento, Calif., one-eighth to James H. Littlehales, Washington, D. C., and one-eighth to Carl A. Hellmann, Washington, D. C.

Application December 14, 1932, Serial No. 647,256

6 Claims. (Cl. 250—20)

This invention relates to an automatic interrupter for broadcast receivers and it comprises in combination with a conventional receiving set, a unit connected to the antenna system thereof and adapted to respond to vibrations of a selected radio frequency different from that to which the conventional receiver is tuned, said interrupter unit utilizing the incoming signal of different frequency automatically to block the electron flow in the radio frequency tubes of the said conventional receiving set, whereby when a signal is received of the predetermined frequency to which the interrupter unit is responsive it is made audible while the initial signal is blocked, but upon cessation of such signal the initial signal will again be rendered audible; all as will be described more fully hereinafter.

It is an object of our invention to provide a receiving set for signals of different frequencies and so arranged that when signals of a predetermined frequency are received the reception of other signals is automatically blocked and such audible reception is automatically resumed upon cessation of the signals of such predetermined frequency.

Another object is to provide an interrupter unit which can be compactly housed within the cabinet of any conventional receiving set, and which utilizes the incoming signal of a frequency different from that to which the conventional receiving set is tuned for automatically rendering audible the signal of predetermined different frequency and simultaneously blocking the broadcast signals as received on the conventional receiving set, while automatically permitting such broadcast signals to resume to produce audible sounds when the predetermined different frequency signals have ceased.

Referring to the drawing wherein is shown in diagram a circuit embodying our invention:

The variable condenser C^1 acting as a high frequency blocking condenser and in conjunction with the radio frequency choke L^1 , blocks all signals to the conventional receiving set from shorting to ground.

The condenser C^1 is adjusted to tune the aerial circuit including also the inductance L_1 to the desired frequency and when a signal of that frequency is picked up by the receiving set antenna it is impressed upon the grid of tube T^1 , a 58

type alternating current variable mu radio frequency pentode tube.

R^1 is a variable resistor, the portion of which to the left of the slider is by-passed by a fixed condenser C^3 for adjusting the bias on T^1 to give the correct volume when the interrupter unit is operating through the audio system of the receiving set. R^2 is a resistor which acts as a bleeder between R^3 and R^1 . R^3 is a voltage drop resistor between the plate lead and screen grid lead for the screen grid potential. C^4 is a fixed by-pass condenser for the screen grid lead.

The tube T^1 amplifies the received signal which, upon passing through the plate lead to the radio frequency coil L^2 is again tuned by a variable condenser C^2 to obtain greater amplification, and upon passing through the voltage blocking condenser C^7 is impressed upon the grid of tube T^2 , a type 56 alternating current detector and amplifier. C^5 is a fixed by-pass and voltage blocking lead for the plate lead of tube T^1 .

The tube T^2 is arranged to act as a detector, and the resistor R^7 and fixed by-pass condenser C^7 give the necessary bias. The resistor R^8 is a grid-to-ground bleeder. The tube T^2 changes the signal from radio frequency to audio frequency and passing through the plate lead P it is connected with the plate lead of the first audio stage in the conventional receiving set as P' to be further amplified. Such connection is the same for a resistance coupled first audio stage receiver of conventional circuit.

A radio frequency choke L^3 with a fixed by-pass condenser C^9 in the plate lead of tube T^2 serves to prevent radio frequency signals from going through to the audio amplifiers.

When a signal is being received by the interrupter unit receiver the following change occurs. Tube T_1 amplifies the incoming signal and impresses this amplified incoming signal upon the detector of the said receiver circuit. This amplified signal also comes through condenser C_6 to the grid of tube T_3 , the signal acting as an applied voltage, alternating in character. Thus tube T_3 acts as a rectifier. During the positive half of each cycle of alternation, the plate of tube T_3 will draw current, and during each negative half-cycle the tube T_3 will not pass current. The resistor R_5 is adjusted to such a value that it will not permit excessive current to flow from the 50

plate of tube T_3 to the ground (chassis). The resistor R_5 also permits a complete circuit from the grids of tubes 1 and 2 of the cooperating conventional broadcast receiving set. The resistor R_6 acts as a radio-frequency choke, preventing the leakage of any radio frequency energies which otherwise might leak through tube T_3 , and keeping the aforesaid radio frequencies from being applied to the grids of tubes 1 and 2 of the 10 said conventional receiving set.

The grids of the radio frequency tubes in the conventional receiving set become more negative with reference to the cathodes of the same tubes at the time the signal is received on the other 15 receiving set, due to the rectified voltage output from tube T_3 . The said output will tend to cut off the plate current from the radio frequency tubes in the conventional receiving set. The tube characteristic of such tubes is completely changed 20 by this and all amplification in the conventional receiving set will cease.

This same output current from tube T_1 flowing through the detector of its receiver or interrupter unit will change this signal, initially of the frequency to which the interrupter unit is tuned, from radio frequency to audio frequency, due to the action of the detector tube T_2 , and the interrupter unit, being connected in the usual manner to the first audio transformer of the conventional broadcast receiver, the signal is amplified and ultimately changed to sound in the usual way. During this time there is no interference 30 from the signal energy of the conventional receiver. The resistor R_4 is a limiting resistor to hold the output of tube T_3 to a predetermined 35 value.

The alternating current voltage impressed upon the grid of tube T_3 , of course, initially is of radio frequency which becomes rectified the same as any other alternating voltage. The rectified or direct current voltage from the plate of T_3 is conveyed through the resistor R_8 to the low potential end of the tuning coil or coils in the said conventional radio receiving set.

R_8 is a high resistance connected from the plate of T_3 to the chassis or ground of the conventional radio receiver. Its purpose is to avoid a direct short circuit of any current flowing from the plate of tube T_3 and also to permit the tubes of the conventional radio receiving set to operate with their customary grid bias whenever no signal is passing through the interrupter unit.

When a signal is received through the interrupter unit the rectifying action of tube T_3 is established immediately and when such signal ceases the rectification also stops at once.

The tube T_2 which is thus used as a control tube, is preferably of the same type as tube T_2 . The plate or anode of tube T_1 is connected to the grid of tube T_3 through the coupling condenser C_6 . When a signal is passing through the tuned circuit of the interrupter unit, said signal produces a small current flow between the cathode and the anode of tube T_3 , thus producing a small voltage drop. This voltage drop is applied to the grids of tubes 2 and 3 of the conventional receiving set and serves to provide a high negative bias which will cut off the anode current in these tubes and thereby effectively prevent said tubes from acting as radio frequency amplifiers in the radio frequency portion of the said conventional receiving set.

The lead wire from the tuning coil L_2 to condenser C_6 which is in series in the circuit, and 75 from the condenser C_6 to the grid of tube T_3 ,

feeds the signal frequency only during the operation of the interrupter unit, which interrupter unit includes T_3 , R_4 , R_8 , R_5 , and R_6 as shown in the drawing.

Thus when no signal is coming through the grid of T_3 , no rectification takes place; the only voltage present on the grid of tube T_3 is a negative voltage supplied by resistor R_4 which is connected to the grid of tube T_3 , and the resistor R_9 which, in turn, is supplied by this negative voltage from the power supply (negative end of R_9).

When no signal is being received on the auxiliary receiver, the interrupter unit is not in operation, but because resistor R_5 (which is connected to resistor R_6 and to the plate of tube T_3) is grounded to the chassis, a normal grid-bias voltage is allowed to flow through said resistor. This bias voltage (approximately 2.5 volts) may be obtained from the conventional broadcast receiver in the manner specified and usual to all conventional broadcast circuits and is preferably obtained in this manner. Between the cathode of any detector or amplifier tube, of the type of tube T_3 , and the ground (chassis) is inserted a resistor, the value of the resistance being determined by the tube characteristic. One side of this resistor, which is negative, is connected to the ground (chassis) and will permit the cathode to become positive. This is due to the current flowing through the tube, the grid of this tube being connected to a coil which is connected to the ground (chassis) by means of a wire leading to the chassis of the receiving set, or else the said coil may be connected to a resistor, which is connected to the ground (chassis), so that the ground will then become negative with respect to the cathode of the same tube. The above explains the term "negative bias".

The voltage action between the grid and plate output of tube T_3 results in the complete and instantaneous interruption of the receiving set on regular broadcast signals and allows the receiving set to function on another signal of a different frequency which is being received through the interrupter unit, such voltage action further causing the receiver automatically and instantly to resume operation on the original signal when the signal to the interrupter unit ceases.

R^4 is a high negative bias control resistor for the grid of tube T_3 while R^6 and R^{10} are adjustable bleeder resistors, and R^9 is a voltage drop resistor.

C^{10} and C^{11} are high capacity by-pass condensers to act as a direct radio frequency short circuit between condensers C_a and C_b to tune coils L_a and L_b of the receiving set.

The filament or heater leads Y from the tubes of the interrupter unit are connected to the Y leads of the receiving set which is of conventional circuit and for that reason is not here described in particular detail except insofar as the interrupter unit is connected to it.

The condensers C^1 and C^2 are semi-adjustable and are initially tuned and set to the desired frequency for operation of the interrupter.

It is to be understood that although in its preferred form our invention includes an interrupter unit responsive to short wave signals such unit may, within the purview of the invention, be responsive to any wave length, either short or long, utilizing any frequency band. Further, the interrupter circuit shown is merely by way of illustration, and may, instead, be adapted for long

distance reception by the addition of radio frequency or intermediate frequency amplification stages.

From the foregoing it will be apparent that our invention provides an efficient and compact but inexpensive means for automatically receiving signals of different frequency from that of the receiving set to which it is connected, and without necessitating the use of a separate antenna system, such means functioning automatically to block the signals of one frequency while those of a selected different frequency are being received and translated into sound, and further functioning automatically to resume the audible reception of the signals of the one selected frequency when those of the other selected frequency have ceased. The center tap of the power transformer is negative with relation to the ground (chassis) due to the resistor R_a . The difference in voltage depends upon the current drawn through the resistor R_a and on the resistance of the said resistor.

What we claim is:

1. In combination with an antenna and a receiver connected thereto, responsive to signals of a selected frequency and comprising radio frequency and audio frequency stages, a second receiver circuit responsive to a predetermined signal of different frequency and also connected to said antenna, a control tube in said second receiver circuit, said control tube having a grid, a cathode and an anode, means normally impressing on said grid a potential negative with respect to the cathode and means whereby the negative potential of the said grid is removed when said second receiver is fed with such predetermined signal energy of different frequency, whereby electron flow from the cathode to the anode of said control tube takes place, thus providing an output of current from the said anode, and connections for applying a negative bias derived from the anode current of said control tube to the grids of the radio frequency tubes of the first receiver, thereby automatically blocking the electron flow in such radio frequency tubes and interrupting the audible reception of the signals to which the first receiver is responsive, during the reception of signals of the selected frequency to which the second receiver circuit is tuned.
2. In combination with an antenna and a receiver connected thereto, responsive to relatively long wave length signals and comprising radio frequency and audio frequency stages, a second receiver circuit responsive to a predetermined relatively short wave length signal and also connected to said antenna, a control tube in said second receiver circuit having cathode, grid and anode electrodes, means for normally maintaining said grid negative with respect to said cathode, means for providing a positive voltage on the said grid responsive to passage of a signal through the said second receiver circuit, thereby establishing a relatively large anode-cathode current in said tube, means including a resistance traversed by such current whereby a voltage drop is provided, and means for applying such voltage drop as a negative bias to the grids of the radio frequency tubes of the first receiver, to temporarily prevent such tubes from amplifying, so as to interrupt the audible reception of the long wave length signals during reception of the selected short wave length signals, and a detector tube in said second receiver circuit, the anode lead of which is connected with the anode lead of the first audio stage in said first-named receiver to

cause the latter to amplify and render audible the signals impressed upon the short wave length receiver circuit.

3. The combination of two radio receivers tuned to be responsive to signals of different radio frequencies, each receiver including tubes having cathode, anode and grid electrodes, certain of said tubes acting as radio frequency amplifiers, an antenna common to said receivers, a control tube having cathode, anode and grid electrodes and connected in circuit with one of said receivers and having an anode connected to at least one of the grids of the radio frequency amplifier tubes of said other receiver, means for applying a voltage on the grid of said control tube produced by and in response to a signal impressed upon the circuit containing such tube, and thus controlling the action of said radio frequency amplifier tubes through their said connection with the anode of said control tube, whereby when a signal is received by the circuit containing the control tube, audible reception by said other receiver will be interrupted.

4. The combination of two radio receivers tuned to be responsive to signals of different radio frequencies, each receiver including tubes having cathode, anode and grid electrodes, certain of said tubes acting as radio frequency amplifiers, an antenna common to said receivers, a control tube having cathode, anode and grid electrodes and connected in circuit with one of said receivers and having an anode connected to at least one of the grids of the radio frequency amplifier tubes of said other receiver, means for applying a voltage on the grid of said control tube produced by and in response to a signal impressed upon the receiver with which the control tube is in circuit, thereby to produce a grid-blocking voltage output from the anode current of said control tube which, being applied through said connection to at least one of the grids of said radio frequency amplifier tubes, interrupts the audible reception of said other receiver.

5. The combination of a plurality of radio receivers tuned to be selectively responsive to signals of different radio frequencies, an antenna common to all of said receivers, a control tube in circuit with one of said receivers and having a grid which is normally maintained at a negative potential with respect to the cathode, but which, when a signal of proper frequency is impressed upon such circuit, produces a corresponding variation of effective impedance of the control tube whereby a pulsating rectified anode current is provided, means to produce a voltage drop from said current, connections between the anode of such tube and the grids of the radio frequency tubes of another receiver, thereby to interrupt the electron flow in said radio frequency tubes and, consequently, to interrupt audible reception through such receiver, by applying said voltage drop as a grid-blocking negative bias on the grids of such tubes through said connections when the anode current in said control tube is increased by the impression of a radio frequency signal upon the circuit in which the control tube is connected, together with an audio amplification system common to all of said receivers.

6. The process of controlling the operation of a first radio receiving set by a second, which consists in tuning the first set to a wave length of signals which are substantially continuously available, whereby said set normally produces an audible response corresponding to said signals, tuning the second set to a wave length of signal-

modulated carrier wave signals which are available only at relatively infrequent intervals, causing said second set to produce an audible response corresponding to said relatively infrequent signals, and at the same time causing the second set to produce a unidirectional voltage upon receipt of said signals, and applying said voltage as a blocking bias in the first set, to in-

terrupt the production of audible response to the continuously available signals thereby, during such infrequent periods of activity of the second set, whereby the second set alone then produces audible sounds.
